ABSTRACT: A pressure-fluid-operated tool has between a pressure source and a pressure-operated valve for releasing pressure to operate a driver, communication via a chamber which is formed within a gastight seal on the tool and between the tool and the workpiece surface only when the tool is properly applied to the workpiece surface.

PRESSURE-FLUID-OPERATED TOOL

This invention relates to pressure fluid operated tools, for example for stapling, nailing, tacking, riveting and drilling.

Such tools are capable of ejecting a fastener, i.e. a staple, nail, tack or rivet at great speed or exerting great force on a tool bit and attempts have been made in the past to introduce safety features into these tools whereby operation can only take place when the tool is properly positioned with respect to a workpiece. These prior proposals have involved a mechanical sensor adjacent to the opening out of which the fastener is ejected, or through which the tool bit is applied, which sensor only permits operation when depressed. However, such a sensor has not been found to be completely foolproof since when working near an edge of a workpiece it is possible to depress the sensor by application of the tool to the workpiece while the opening is actually clear of the workpiece. Furthermore, some of the prior proposals have included sensors which can be depressed by hand while the tool is away from the workpiece. In both cases the fastener can be ejected into free flight or the tool bit can be applied somewhere other than desired with the possibility of injury to personnel.

An object of the invention is to make it impossible to operate the tool unless the opening is placed over a workpiece surface, i.e. so that the workpiece surface completely covers the opening.

According to the invention a pressure-fluid-operated tool comprises sealing members defining a recess open to atmosphere, the recess surrounding an opening through which a work member is to emerge; a valve, operable to open communication between the recess and a source of pressure fluid; a pressure-fluid-operated valve in communication with the recess; and a pressure-fluid-operated driver for the work member and communicable with the source of pressure fluid on operation of the pressure-fluid-operated valve, the sealing members being engageable with a surface of the workpiece to transform the recess into a chamber closed from the atmosphere so that pressure fluid will pass from the recess to the pressure-fluid-operated valve for operation thereof on operation of the valve which is operable to open communication between the recess and the source of pressure fluid.

The tool according to the invention can only operate when a continuous workpiece surface engages all the sealing members since otherwise the pressure fluid will merely be lost to the atmosphere. This means that the opening must be covered by the workpiece surface before operation can take place. This completely avoids the risk of untimely operation of the tool due to incorrect positioning of the tool against a workpiece, or foolhardiness.

In order that the invention may be more clearly understood it will now be described, by way of example, with reference to the accompanying drawings, in which:

FIG. 1 is a fragmentary sectional view of a pneumatically operated stapling tool; and

FIG. 2 is a perspective view, partially broken away and to an enlarged scale, of a detail of FIG. 1.

In FIG. 1 a portion of a pneumatically operated stapling tool is illustrated and the magazine for the staples, constituting work members, has been omitted. The tool comprises hollow casting including a handle portion 1 enclosing a chamber 2 which is connected with a source of compressed air, a lower portion 3 enclosing a storage chamber 4 which is unconnected with the chamber 2, and a generally cylindrical portion 5 enclosing a chamber 6 in which a cylinder 7 is sealingly mounted. The cylinder has its lower end 8 fitting within a seat 9 at the lower end of the chamber 6 and is sealed by an annular resilient buffer 10 within the cylinder at its lower end. The cylinder 7 is also sealed externally by an O-ring 11 to divide the chambers 2 and 4.

At the upper end of the portion 5 the chamber 6 is open and has a flanged portion 12 fitted thereover. The portion 12 has a spigot 13 depending into the open upper end of the chamber 6

and the spigot has a cylindrical chamber 14 therewithin from the bottom of which radial passages 15 extend outwardly. Below the chamber 14 and the passages 15 the spigot 13 is reduced in diameter to provide a neck 16 from which a narrow boss 17 depends into the top of the cylinder 7. Fitted about the boss 17 is a disc 18 apertured at 19 and the perimeter of this disc is seated against the top of the cylinder 7 and is sealed thereagainst by an O-ring 20.

An annular piston valve member 21 is guided for movement 10 in an annular chamber 22 between the upper end of the chamber 6 and the spigot 13 and is sealed between these members by O-rings 23 and 24. The valve member 21 includes a sealing member 25 for valving cooperation with the periphery of the disc 18 and an O-ring 26 for valving cooperation with the spigot 13 below the passages 15. The chamber 22 above the valve member 21 communicates, via passages 27 and 28, with an annular chamber 29 within a hollow cylindrical insert 30 and about a waisted portion 31 of a pressure-fluid-operated spool valve member 32. At opposite ends of the waisted portion 31 are O-rings 32 which depending on the position of the valve member 32 puts the chamber 29 into communication with either the chamber 6 or a passage 33 in the flanged portion 12. The chamber 14 and the passage 33 both open to atmosphere and a hood 34 is provided over the flanged portion 12 to direct exhausted air away from the handle portion 1.

The spool valve member 32 has a piston 34 movable within a cylindrical chamber 35 and is sealed therewithin by an O-ring 36. The upper end of the chamber 35 opens into the chamber 6 while the lower end communicates with a duct 37 which leads to the interior 38 of a hollow elongated member 39, (FIG. 2) having an enlarged yoke 40 at its lower end, which fits about a staple guide body 41. The interior 38 of the member 39 is open at its lower end and houses a tube 42 which extends along the length of the member 39. The tube 42 is connected with a duct 43 within the casting and the duct 43 opens into the chamber 6. The lower end of the tube 42 has a tubular insert 43' therein which houses a compression spring 44 and a ball valve member 45 which is urged towards a closed position by the spring 44. At the lower end of the member 39 a rectangular sealing member 46 extends about its periphery and within this member 46 another smaller rectangular sealing member 47 extends about the periphery of the lower end of the staple guide body 41 so as to define a recess between the members 46 and 47, with which recess the spool valve member 32 is in communication.

The staple guide body 41 has its upper end fitted within the casting and has a staple guide passage 48 which at its upper end opens into the cylinder 7 within the annular buffer 10 and at its lower end forms an opening surrounded by the recess defined by the members 46 and 47. A bladelike driver 49 is movable along the passage 48 which at its upper end is provided with a groove 50 which can be opened and closed by the driver 49. A side gap 51 is provided within the body 41 for the introduction of staples from the magazine. The driver 49 depends from a spigot 52 of a ram piston 53 movable along the cylinder 7 and sealed therewithin by an O-ring 54. The cylinder 7 also includes openings 55 about its lower end in communication with the chamber 4 and openings 56 a little further up the cylinder closed by an O-ring 57 which has space to expand and open the openings 56.

A cycle of operation will now be described starting from the condition of the tool shown in FIG. 1. In this condition, since the chamber 2 is continuously in communication with a source of compressed air, the chambers 6 and 22 and the duct 43 are under compression while the chamber 4 and the interior of the cylinder 7 under the piston 53 are open to atmosphere via the openings 55 and the groove 50. The space above the piston 53 and the duct 37 are also open to atmosphere.

On placing the sealing members 46 and 47 in complete engagement with a surface of a workpiece the recess defined by the sealing members is transformed into a chamber closed from the atmosphere so that on pressing the tool onto the surface the ball 45 is unseated and compressed air is fed from the

duct 43 and the tube 42 into the interior 38 of the member 39 whence it is led into the duct 37. Since the effective cross-sectional area of the lower end of the piston 34 is higher than that of its upper end the spool valve member 32 is forced upwards to place the chamber 22 in communication with the atmosphere. The pressure in the chamber 6 then forces up the piston valve member 21 simultaneously to close the space above the piston 53 from atmosphere and open it to the pressure in the chamber 6.

This suddenly forces the piston 53 down the cylinder 7 so that initially the driver closes the groove 50 and the air under the piston and within the chamber 4 is slightly compressed. The driver continues its movement to eject a staple through the opening at the lower end of the passage 48 into the workpiece. When the piston 53 reaches the buffer 10 it just passes the openings 56 and the compressed air above the piston expands the O-ring 57 so that the chamber 4 is opened to the compressed air.

On lifting the tool from the surface of the workpiece the ball 45 is urged towards its seats and the duct 37 is exhausted so that the spool valve member 32 moves down again. In so doing the chamber 22 is put into communication with the compressed air in the chamber 6 so that the piston valve member 21 is moved down to close the space above the piston 53 from communication with the chamber 6 and open communication with the atmosphere. The compressed air in the chamber 4 then forces the piston 53 up again until the driver 49 opens the groove 50 to exhaust whereby to bring the pressure below the piston and within the chamber back to atmospheric.

It will be seen that in order to secure operation of the tool the ball 45 must be depressed and the sealing members 46 and 47 must be properly engaged with a surface. If the ball 45 is merely depressed without the sealing members 46 and 47 being properly engaged by the surface the compressed air merely issues from the tube 42 and is not fed into the duct 37.

In a modification the ball valve member 45 may be omitted

and the duct 43 include a valve manually operable for example by a trigger.

The guide passage 48 is oblong in cross section in order to suit the staples. The tool could however be modified to take other fasteners such as nails tacks or rivets, the cross section of the opening being shaped to suit such items. The tool may also be modified into a pneumatically operated drill, a work member in the form of a bit being attached to the driver for application to a workpiece through the opening and means being provided to deliver a succession of pressure impulses to the driver.

1. I claim:

1. A pressure-fluid-operated tool comprising: sealing members defining a recess open to atmosphere, the recess surrounding an opening through which a work member is to emerge; a valve, operable to open communication between the recess and a source of pressure fluid; a pressure-fluid-operated valve in communication with the recess; and a pressure-fluid-operated driver for the work member and communicable with the source of pressure fluid on operation of the pressure-fluid-operated valve, the sealing members being engageable with a surface of the workpiece to transform the recess into a chamber closed from the atmosphere so that pressure fluid will pass from the recess to the pressure-fluid-operated valve for operation thereof on operation of the valve which is operable to open communication between the recess and the source of pressure fluid.

2. A tool according to claim 1, wherein the valve which is operable to open communication between the recess and the source of pressure fluid is arranged to be operated by depression of the work member as the sealing members are engaged with the surface of the workpiece.
